United States Patent Office

Des. 219,386
Patented Dec. 8, 1970

219,386

TELEVISION TAPE TRANSPORT

Jack R. Goodrich, Newark, Calif., assignor to Ampex Corporation, Redwood City, Calif., a corporation of California

Filed Nov. 28, 1969, Ser. No. 20,309

Term of patent 14 years

Int. Cl. D14—02, 03

U.S. Cl. D26—14

The figure is a perspective view of the front and right side of a television tape transport showing my new design, the left side being a mirror image of the right side, and the top, back and bottom being conventionally plain.

I claim:

The ornament design for a television tape transport, substantially as shown and described.
